(57) **CLAIM**

The ornamental design for audio video shelving unit, as shown and described.

DESCRIPTION

FIG. 1 is a front perspective view of the audio video shelving unit;

FIG. 2 is a front view thereof;

FIG. 3 is a rear view thereof;

FIG. 4 right side view thereof (the left side being a mirror image of the right side view);

FIG. 5 is a top plan view thereof; and,

FIG. 6 is a front perspective view of a second embodiment of the audio video shelving unit.

The broken lines shown in the drawing are for illustrative purposes only and forms no part of the claimed design.
